PROCESS FOR THE COMPRESSION OF GASES

Aaron K. Redcay, Mount Lebanon, Pa., assignor to Gulf Oil Corporation, Pittsburgh, Pa., a corporation of Pennsylvania

Application August 7, 1952, Serial No. 303,181

1 Claim. (Cl. 230—209)

This invention relates to a process for the compression of gases and more particularly to an improved method for the handling of a gas or mixture of gases undergoing compression in a centrifugal compressor.

In the case of a purely adiabatic compression of a gas, which is, by definition, one in which no heat is added to or removed from the gas during compression, there is nevertheless an increase in the temperature of the gas. This increase in temperature is a manifestation of a change in form of the mechanical work done on the gas into heat energy within the gas. In addition, the inefficiency of a centrifugal compressor changes gas conditions within the compressor so that in practice an adiabatic compression is not achieved. For example, various energy losses taking place within the compressor such as mechanical friction, gas friction and turbulence are all transformed into heat and raise the temperature of the gas beyond that calculated from adiabatic compression conditions.

This increase in temperature or internal energy resulting from those causes discussed above may have particularly detrimental effects. In the case of any gas the increased internal energy of the gas makes further compression more difficult and expensive by virtue of the extra work required. In the case of many normally gaseous hydrocarbons, particularly hydrocarbon-containing gases such as inflammable gases like gas mixtures containing acetylene; and refinery gases and those derived from the cracking of normally gaseous hydrocarbons, such as ethane and propane, at the elevated temperatures resulting during compression, the gases or mixtures of gases may be thermally sensitive; that is, they may be reactive at the temperatures attained during compression to undergo decomposition, alkylation, or polymerization reactions and the like.

Since the foregoing hydrocarbon-containing gases contain valuable constituents, such as ethylene, it has become customary to subject such gases to various separation processes to recover the valuable constituents therefrom. The separation processes employed have included fractional distillation, oil absorption or extraction, or combinations of such processes. In any of these processes, it is necessary to at least partially liquefy the initial gaseous mixture, such liquefaction involving compression of the gases followed by cooling. In compressing thermally sensitive hydrocarbon-containing gases for the purpose of liquefying them, the controlled temperatures attained during compression tend to cause thermal reactions, thereby resulting in a loss of valuable components of the gaseous mixture and/or operating difficulties with the compressors and in the separation process. For example, a gaseous mixture to be subjected to a separation process may contain hydrogen, methane, ethylene, ethane, propylene, propane, butenes, butanes, pentenes, pentanes, and related dienes, such as propadiene, butadiene, pentadiene, cyclopentadiene and the like. Such a mixture is susceptible to such undesirable thermal reactions as polymerization and alkylation during compression. The diene hydrocarbons

can polymerize either by themselves or in a copolymerization reaction with the mono-olefinic hydrocarbons to form solid polymers which tend to plug up subsequent separating apparatus and represent a loss of valuable components. Similarly the diene hydrocarbons or the mono-olefinic hydrocarbons can become involved in alkylation reactions with each other or with the saturated hydrocarbons, again resulting in a loss of valuable components.

Conventional methods for controlling the increase in temperature of gases being compressed have employed multistage compressors with interstage cooling by means of indirect heat exchange. The volume of ordinary cooling media in such a case is so great, however, as to entail a large capital investment for coolers. Furthermore, a considerable increase is required in the number of compression stages to achieve sufficient final compression of the gases.

It is therefore an object of this invention to compress a thermally sensitive, hydrocarbon-containing gaseous mixture while avoiding thermal reactions of such mixture.

It is also an object of this invention to limit the increase in temperature normally encountered in the centrifugal compression of a thermally sensitive hydrocarbon-containing gas.

A further object of this invention is to reduce the power required to compress a thermally sensitive, hydrocarbon-containing gas in a centrifugal compressor.

These and other objects are achieved by the present invention wherein, in the centrifugal compression of hydrocarbon-containing gases also containing thermally sensitive constituents, there is injected into the gases undergoing compression a vaporizable liquid. The vaporization of the vaporizable liquid in the stream of gases undergoing compression serves to cool the compressed gases, and thus produces a temperature level within said gases lower than the temperature which would otherwise be attained by reason of the normal heat of compression. Thermal reaction of the thermally sensitive gases is thereby avoided.

Furthermore, as compared with conventional compression, less power is required to compress the gases to the same pressure.

In order more fully to describe my invention reference is made to the accompanying drawings in which:

Fig. 1 is a cross-sectional view of a standard centrifugal compressor, four pressure stages of compression being represented, in which liquid injectors have been incorporated;

Fig. 2 is a diagrammatical representation of operating conditions and effects where gas compression is achieved without either liquid injection or interstage cooling;

Fig. 3 is a diagrammatical representation of operating conditions and effects where gas compression is achieved with interstage cooling;

Fig. 4 is a diagrammatical representation of operating conditions and effects where liquid is injected in accordance with my invention.

The centrifugal compressor shown in Fig. 1 is of standard design. The gases to be compressed enter through suction inlet 10 at which point vaporizable liquid may be injected through atomizer 11. The vaporizable liquid vaporizes within the stream of gases to be compressed, and in so doing an amount of heat equal to the heat of evaporation of the vaporizable liquid is abstracted from the stream of gases being compressed, thereby cooling the gases. The cooled gases then pass through inlet guide vane 12 into impeller 13 attached to rotating shaft 14. The high angular velocity of the shaft and impeller throws the gases centrifugally through passage-way 15 into deflector 16 at which point more vaporizable liquid can be injected through atomizer 17 to achieve a direct cooling of the gases being compressed in the same

manner described above. Deflector 16 then directs the fluid from the free space within the deflector towards the center of the next rotating impeller 18. The gases then pass successively through stages represented by impellers 19 and 20, in each of which the gases undergo further compression with cooling between pressure stages by the injection of vaporizable liquid from atomizers 21 and 22. Finally, the compressed gases are discharged through outlet 23. Elements 24 through 28 inclusive, represent drain plugs located in the lower portion of the compressor casing for removal of any liquids that may collect at those points during compression.

As vaporizable liquids for injection into the gases being compressed I can employ any liquid which is vaporized to a substantial extent at the pressures and temperatures existing at the point of injection. For example, water can be used to good effect, sufficient vaporization taking place even at temperatures below its boiling point at the pressure involved to exert a cooling effect. A liquefied normally gaseous hydrocarbon, such as liquid ethane or propane, or low boiling normally liquid hydrocarbon, such as pentane or hexane can also be employed. In some cases mixtures of water and hydrocarbons can be employed, or water can be employed in some compression stages such as the initial stages, and hydrocarbons in the other compression stages, such as the later stages. It is preferred to employ as the vaporizable liquid water obtained from cooling the compressed gas to at least partially liquefy the water component.

The following example shows the effect of water injection in the compression of a hydrocarbon-containing gaseous mixture, the results being illustrated diagrammatically in Figs. 2, 3 and 4. The charge gas has the following composition:

Charge gas	
Component:	Vol. percent
Hydrogen	28.1
Methane	7.6
Ethylene	31.9
Acetylene	0.4
Ethane	26.1
Propylene	1.2
Propane	0.5
Butylene	0.5
Water	3.7
	100.0

jection or interstage cooling the gaseous mixture requires seven stages of compression to be raised from 33.7 p. s. i. a. to 85 p. s. i. a., with a power requirement of 1740 horsepower. In compressing the gases through the seven stages they are heated from an initial temperature of 105° F. to a discharge temperature of 280° F. Such a discharge temperature will tend to cause thermal reaction of the thermally sensitive constituents.

Fig. 3 indicates that, to achieve the same degree of compression with interstage cooling of the gases at the points indicated, eight stages are required with a horsepower requirement of 2220. The discharge temperature of the gases is 214° F.

When water is injected into the gases being compressed in accordance with my invention, as represented in Fig. 4, only six stages of compression and only 1680 horsepower are required to compress the gases to the same pressure, namely, 85 p. s. i. a., achieved in the methods shown in Figs. 2 and 3. The discharge temperature of the gases is 219° F. It is to be borne in mind that the discharge temperature and power requirements may be even further reduced by injection of water into a greater number of pressure stages.

The foregoing example clearly shows the temperature control achieved and the power savings and reduction in compressor size that are made possible by the injection of vaporizable liquids into a stream of a thermally sensitive, hydrocarbon-containing gaseous mixture undergoing compression. Such temperature control effectuates economies by preventing (1) costly losses of a portion of reactive gases through their polymerization, alkylation and the like, and (2) operating difficulties that may be caused thereby. The reduction in compressor size that is possible by the method of my invention is another economy attained. In addition, heavy and expensive heat exchangers and piping such as are used in Figure 3 to achieve indirect cooling, can be eliminated with resultant reduction of installation costs.

Although I have disclosed the use of water as the vaporizable liquid in the specific example, it will be obvious that any other vaporizable liquid which vaporizes at the pressures and temperatures existing at the point of injection can be employed. In addition, compressors having more or less pressure stages than that shown in Figure 1 can be employed. Furthermore, the vaporizable liquid can be injected into the gases entering the suction of the compressor, directly into the compressor

In the example and in Figs. 2, 3 and 4, the theoretical horsepower requirement of the various methods represented therein is the calculated horsepower required to compress the gases delivered by the compressor through the specified range of pressures. The actual horsepower requirement is based on a 75 percent efficiency.

Fig. 2 shows that without either vaporizable liquid in-

70 itself, between the stages of a multistage compressor, or at any or all of these points. Moreover, an amount of vaporizable liquid can be injected into the stream of gases undergoing compression in excess of that completely vaporized. The unvaporized liquid would be discharged in the compressed gases at the compressor outlet.

Obviously many modifications and variations of the

invention as hereinbefore set forth may be made without departing from the spirit and scope thereof and therefore only such limitations should be imposed as are indicated in the appended claims.

I claim:

A method of centrifugally compressing a gaseous mixture containing as constituents hydrogen, methane, acetylene, ethylene, ethane, propylene, propane, butanes, butylenes, related dienes and water while controlling the temperature of compression to avoid reactions to which the constituents would be subject under normal uncontrolled compression, which comprises compressing said mixture, injecting into said mixture a vaporizable liquid, which liquid is vaporized to a substantial extent at the pressures and temperatures existing at the point of in- 15

jection, atomizing said vaporizable liquid, and continuing the injection and atomization until said vaporizable liquid is vaporized to a substantial extent in said gaseous mixture, thereby lowering the temperature of the aforesaid mixture to avoid thermal reactions of the constituents in the mixture undergoing compression.
